UNITED STATES PATENT OFFICE.

EDWARD R. BARRETT, OF DETROIT, MICHIGAN, ASSIGNOR TO WOOD HYDRAULIC HOIST AND BODY COMPANY, OF DETROIT, MICHIGAN, A CORPORATION OF MICHIGAN.

LIFTING AND DUMPING BODY APPARATUS.

Application filed June 12, 1924. Serial No. 719,534.

This invention relates to a lifting and dumping body apparatus designed for either the tilting of a body carried on a motor truck or like vehicle so as to dump its contents by gravity or for the simultaneous lifting of the body above its normal position and tilting thereof for gravity dumping.

The present invention consists of various novel constructions, combinations and arrangements of parts for practically attaining these ends in a new and effective manner and one which is particularly efficient in operation. In addition, the construction includes means whereby the body may be simultaneously elevated and tilted to different positions, one of which is an extreme high position and the other an intermediate high position lower than the first.

For understanding of the invention by means of which these ends are obtained and of the constructions embodying the invention, reference may be had to the following description taken in connection with the accompanying drawing in which,

Fig. 1 is a side elevation of a motor truck with a dumping body thereon provided with the mechanisms of my invention, the body being shown in lower horizontal position.

Fig. 2 is a like view showing the body elevated to its highest position and tilted for gravity dumping.

Fig. 3 is a fragmentary perspective view showing the body in its uppermost tilted position.

Fig. 4 is a transverse fragmentary vertical section through the mechanism back of the hydraulic cylinder used therewith.

Fig. 5 is a fragmentary longitudinal section through the apparatus, the same being in its collapsed position or when the body lies horizontal.

Fig. 6 is a like view showing the apparatus after it has moved to partly elevate the body.

Fig. 7 is a view similar to Fig. 5 illustrating the disconnection of certain elements of the apparatus such as is done when the body is to be merely tilted and not elevated.

Fig. 8 is a fragmentary plan view of the apparatus, the body being removed.

Fig. 9 is a vertical section showing the body fully tilted but not elevated and is the position the parts take on operation of the apparatus, with certain parts disconnected as previously described with reference to Fig. 7.

Fig. 10 is a view similar to that shown in

Fig. 9, but with the body elevated as well as tilted, the elevation being to the intermediate position, and

Fig. 11 is a somewhat modified construction showing a partial section or elevation of a construction serving the same purposes as those shown in Figs. 2 and 3, but equipped with means for moving the body forward simultaneously with its elevation and tilting.

Like reference characters refer to like parts in the different figures of the drawings.

The construction is adapted to be applied to a motor vehicle indicated at 1 and having chassis side frame members 2 mounted parallel to each other and in substantially a horizontal plane. At the rear ends of the side frame members, a built-up cross beam is used comprising rear and front channels 3 and 4 with an upper plate 5 bridging and connecting the same. The built-up cross member or beam lies between and over the rear ends of the chassis frame members 2 and is permanently secured thereto. In front of the beam is a cross bar 6 of angle iron, in front of the cross bar 6 is a second cross bar 7 of angle iron, in front of the cross bar 7 is a third cross bar 8 also of angle iron and in front of the bar 8, a front cross bar 9 of channel iron which lies directly back of the cab of the motor vehicle or truck. The bars are spaced apart as shown in any of the Figures 2, 6 or 8 and bars 6 and 7 serve as supports for parallel tracks 10 which at their rear ends are slightly elevated resting on supporting blocks 11 attached to the cross bar 6.

A cylinder 12 is located lengthwise of the chassis and substantially midway between its side frame members 2, the front end having any suitable connection to the channel bar 9 while its rear end extends substantially to the front ends of the tracks 10. A piston is located within the cylinder and a piston rod 13 connected to the piston passes outwardly at the rear end of the cylinder. At its rear end it has a permanent connection with a cross head 14 each end of which is provided with a spindle 15 for the rotatable mounting of rollers 16, 17 and 18. The rollers 16 are adapted to ride on the tracks 10. The rollers 17 are at the outer ends of the spindles and the rollers 18 are located between rollers 16 and 17.

Two brackets 19 are permanently secured in spaced apart relation on the upper side

of the plate 5. Two side bars 20 of channel shape are provided at their rear ends with blocks 21 extending a short distance back of the side bars 20 and are pivotally mounted on a cross shaft 22 which in turn is mounted on and extends between the brackets 19. To each of side bars 20 a cam member 23 is permanently secured, the under edges curving downwardly and to the rear as shown. With cam members 23 positioned so that the rollers 17 come against the under edges thereof, it is evident that on rearward movement of the cross head 14 with the rollers mounted thereon, rollers 16 running on tracks 10 and rollers 17 bearing against the cam edges of members 23, the side bars 20 will be turned upwardly about the axis of the shaft 22. And if nothing but a simple tilting action of the body was desired it would be merely necessary to mount the body above and on the side bars 20. This construction so far described, however, is the subject matter of a patent by Logan T. Wood, No. 1,502,534, issued July 22, 1924 and while forming necessary elements of the present construction, is not in itself the subject matter of this application.

Two rods 24 are pivotally connected at their front ends to suitable brackets carried on the cross bar 8 and extend to the rear therefrom. A sleeve 25 is slidably mounted on each rod 24. Each rod carries a nut 26 at its rear free end and there is a coiled spring 27 disposed around each rod between each sleeve 25 and the nut 26. A second rod 28 is pivotally connected at its rear end to each of the side bars 20 and extends forwardly to the sleeve 25 having permanent connection thereto at its front end as best shown in Figures 2 and 3. When the side bars 20 are tilted upwardly and, as will later appear, any tendency for the construction to over-balance to the rear and the entire structure move about the axis of rod 22 rearwardly is checked by the construction just described, which acts as a stop against such rearward tilting beyond a desired point.

Two bars 29 of channel formation are located one at the outer side of each of the side bars 20. A rod 30 passes through the front ends of the bars 20 and also through the front ends of the bars 29 whereby a pivoted connection between bars 20 and 29 is made. In practice a spacing block 30* is located between the webs of the two channel bars 20 and 29. Cross sills 31, also of channel iron, preferably, are attached in spaced apart relation to and lie over and between the two bars 29. In addition, two angle iron cross bars 32 lie over and above the bars 29 and are secured thereto to serve as additional supports for tracks 33 which are located one inside of each bar 29. These tracks 33 are conveniently formed from angle iron and have horizontal legs to serve

as tracks for rollers as will later appear. The front end portions of the horizontal legs are curved downwardly and forwardly at 33* as best shown in Figures 5, 6 and 7. A body 34 is located above and permanently secured to cross sills 31. The body is of any well known and conventional design, and its specific structure need not be entered into in the present application.

On the inner side of each cam member 23 an arm 35 is located which is pivotally connected at its upper rear corner, the pivot 36 preferably passing through the cam member 23 and being permanently secured to the web of the adjacent side bar 20. In the lower position of the body, as shown in Fig. 5, the upper edges of arms 35 lie under the rollers 18. A link 37 at its front end is pivotally mounted on the same pivot pin 36, one for each arm 35. A second link 38 is connected to the arm 35 below and in front of the pin 36, a removable pin 39 being passed through an aligned opening 39* in the arm 35 and the front end of the link 38. At the rear ends of the links 37 and 38 a built-up structure is mounted, comprising two spaced apart connected plates 40 substantially of a diamond shape.

A rod 41 lies between these built-up structures at the rear ends of the two pairs of links 37 and 38 and passes through the built up structures and also through the rear end of the links 38. The rear ends of links 38 are enlarged, and the rear ends of links 37 are bifurcated to have a part pass by each side of the enlarged end of link 38 and a removable pin 42 passes through the plates 40, the bifurcated ends of link 37 and also through the link 38 as best shown in Figure 8. A roller 43 is rotatably mounted between plates 40 at the extreme rear ends thereof, these rollers bearing against the horizontal portions of the tracks 33 previously described. It is evident that openings must be made through the plates 40 to pass the pins 42. These openings are shown in 42* in Figure 10. In addition other openings 44 are made in these plates for the passage of the pins 42 when it is desired to change the relative positions of the plates 40 and the links 37 and 38. In Fig. 10 this is shown, said plates 40 being turned substantially at almost right angles to the position occupied as shown, for instance in Figure 6.

With a construction as described, when the piston rod 13 and the trundle at its end comprised of cross head 14 and the various rollers mounted thereon are moved rearwardly, side bars 20 are elevated about the pivot axis of shaft 22. Simultaneously with such movement the rollers 18 bear against the ends of arms 35 and turn the arms with the connected links 37 and 38 about the pivots 36, and arms 35 and links 37 and 38 be-

ing in effect a rigid lever when connected together. It is evident the rear ends of links 37 and 38 are elevated and at the same time impelled forwardly, whereupon the 5 rollers 43 carried on the plates 40, in turn carried by links 37 and 38, bear against the tracks 33 and lift the rear end of the body which is being simultaneously elevated at its front end due to the lifting of the front ends 10 of the side bars 20 and the front ends of the bars 29 connected thereto. This is fully shown in Figure 6. The first movement of the body 34 accordingly is upward with little or no tilting of the front end thereof; 15 but with continued movement, the elevation of the front end of the body over the rear end increases until finally, as shown in Fig. 3, the front end of the body is elevated to a considerable distance over the rear end and 20 the rollers 43 bear against the curved portions 33^a of tracks 33. The body is thus elevated and tilted and its contents may be dumped by releasing the end gate of the body as is usual with constructions of this 25 character. The rods 24 and 28 with the connections between them hold the body from over-balancing to the rear.

The position of the parts as shown in Fig. 3 is the extreme upper position that the 30 body can take. If it is desired to elevate and tilt the body to an intermediate position, the plates 40 are connected to links 37 and 38 by passing the pin 42 through the 35 openings 41 in said plates whereupon the length of lever arm from pivots 36 to the highest point of roller 33 is reduced with a consequent less elevation of the body, as is evident.

Many times it is not necessary to elevate 40 the body when it is tilted. In such cases links 38 are disconnected from arms 35 as shown in Fig. 7. When this is done the only mechanism that comes into play is that of rollers 17 against the lower edges of cam 45 members 23. The arms 35, links 37 and 38 and devices carried at the ends of said links are wholly inoperative and the body is merely tilted about the axis of shaft 22 as shown in Fig. 9.

50 In Fig. 11 a somewhat modified form of construction is shown. The side bars 20 are pivotally mounted at 22 on brackets 19^a and at their front ends a cross shaft 45 is mounted on arms 46 permanently secured to the 55 side bars 20. Rollers 47 are mounted on the shaft 45 to run between the flanges of the bars 29 and links 48 connect adjacent bars 20 and 29 as shown in Fig. 11, the effect of which is on the simultaneous tilting and elevation of the body to move the bars 29 forward on rollers 47 thereby carrying the body 34 forward. With such construction there is little need to use the safety device comprising rods 24 and 28 with intermediate parts between them as the center of grav-

ity of the load will be maintained in sufficiently forward position that it will not pass back of the axis of shaft 22.

This construction provides for the simultaneous lifting and tilting of a dumping body with a provision for merely tilting the body if that is desired through a few simple disconnections of parts, and with a provision for elevating and tilting the body to an intermediate position below the extreme 70 upper position if desired. The construction is practical and operative, durable and efficient. The invention is defined in the appended claims and is to be considered as comprehensive of all forms of structure 75 coming within the scope of said claims.

1 claim:

1. In combination with a truck frame, two spaced apart side bars pivotally connected at their rear ends to the frame and parallel- 80 ing the chassis side frame members of the truck frame, a cam attached to each side bar and extending below the same, tracks on the truck frame, a trundle mounted to move over the tracks and carrying rollers to run 85 on said tracks, other rollers to run under the camis to thereby tilt said side bars, and other rollers mounted between the first and second rollers, a body located above the said side bars, means for connecting the body at its 90 front end with the said side bars whereby said body at its rear end may be elevated about the front ends of the side bars, means connected with each of the side bars adapted to be actuated by said last mentioned 95 rollers on movement of said trundle over the tracks to operate against the under side of the body at its rear portion to automatically 100 elevate the rear end of the body with the tilting and elevation of the front end 105 thereof.

2. In combination, a truck frame, side bars pivotally connected in spaced apart relation to the truck frame to be tilted upwardly about their pivotal connection, a 110 truck body mounted for tilting movements about the front ends of said side bars, a trundle movably mounted on the truck frame to move lengthwise thereof, means attached to said side bars with which said trundle engages to tilt the said side bars, and additional means actuated by the trundle and operatively engaging with the body for automatically elevating the body at its rear end 115 as the said side bars are tilted by said trundle.

3. In a device of the class described, a truck frame, side bars pivotally mounted at their rear ends on the truck frame, said bars being spaced apart, additional bars pivotally connected at their front ends to the front ends of the side bars, a truck body carried on and above said additional bars, tracks secured below the body, means for 120 tilting the side bars about their pivotal con- 125

- nections, and means mounted on each of the side bars simultaneously actuated by the means that tilts the side bars for engaging against said tracks to elevate the rear portion of the body with the tilting and elevation of the said side bars. 65
4. In a device of the class described, a truck frame, two spaced apart side bars pivotally connected at their rear ends at the rear portion of the truck frame, two additional bars pivotally connected at their front ends with the front ends of the side bars and lying one alongside each side bar, cross sills attached to and above said additional bars, a truck body carried by the cross sills, tracks attached to and lying under the cross sills, a lever construction pivotally mounted between its ends on each side bar, a roller at the rear end of each lever construction bearing against a track, cams attached to and depending below the side bars, a trundle for moving longitudinally of the truck frame, tracks carried on the truck frame, rollers on the trundle to bear on the truck frame tracks, other rollers to ride under the cams, and still other rollers to ride over the upper edges of the front ends of the lever constructions, substantially as and for the purposes described. 70
5. In a device of the class described, a truck frame, two spaced apart side bars pivotally connected at their rear ends to the rear portion of the truck frame, two additional bars having pivotal connections at their front ends with the front ends of the side bars and lying one alongside each side bar, cross sills attached to and above said additional bars, a truck body carried on the cross sills, tracks attached to and lying under the cross sills and paralleling the said additional bars, a lever construction pivotally connected between its ends to each of the side bars, a roller mounted at the rear end of each lever construction, said roller being carried on an adjustably connected mounting attached to the rear end portion of the lever construction whereby the roller may be located in two different positions with respect to the rear end of said lever construction, said rollers bearing against the tracks, means for tilting the side bars about their pivots, and means for simultaneously operating the lever constructions to turn the same about their pivotal mounts and elevate the rear ends of said lever constructions and rollers carried thereby, substantially as described. 75
6. In a device of the class described, a truck frame, two spaced apart side bars pivotally connected at their rear ends to the rear portion of the truck frame, two additional bars adapted to lie one alongside each of the side bars having pivotal connections at their front ends with the front ends of the side bars, a truck dumping body carried on and above the said additional bars, a lever construction pivotally mounted between its ends on each side bar, a roller at the rear end of each lever construction, means for mounting the rollers on the lever constructions so that the same may be adjusted to a plurality of different positions with respect to the lever constructions, tracks carried under the body and fixed with respect thereto against which said rollers bear, and means for simultaneously tilting the side bars upwardly and turning the lever constructions to elevate the rear end thereof and attached rollers. 80
7. In an apparatus of the class described, a truck frame, two spaced apart side bars pivotally mounted at their rear ends on said truck frame, two additional bars lying one alongside each of the side bars, means pivotally connecting the side and additional bars at their front ends, a truck body carried on and above the said additional bars, tracks located under and fixed with respect to the body, an arm pivotally connected to each of the side bars and extending forward from its pivot, a link mounted on said pivot and extending rearwardly, a second link detachably connected to the arm and extending rearwardly substantially parallel to the first link, means for connecting the links at their rear ends, and a roller mounted at the rear ends of the connected links, said rollers bearing on said tracks. 85
8. In an apparatus of the class described, a truck frame, two spaced apart side bars pivotally mounted at their rear ends on said truck frame, two additional bars lying one alongside each of the side bars, means pivotally connecting the side and additional bars at their front ends, a truck body carried on and above the said additional bars, tracks located under and fixed with respect to the body, an arm pivotally connected to each of the side bars and extending forward from the pivot, a link mounted on said pivot and extending rearwardly, a second link detachably connected to the arm and extending rearwardly and substantially parallel to the first link, two plates located one at each side of the ends of the links, means for pivotally mounting said plates on the second of said links whereby the same may be adjusted to different positions, means for securing said plates to both of the links in a plurality of different positions, a roller rotatably mounted between the plates, said rollers bearing on the tracks, and means to simultaneously tilt the side bars upwardly and to the rear and turn the said arms downwardly about their pivots with a consequent elevation of the links and attached rollers. 90
- In testimony whereof I affix my signature.
- EDWARD R. BARRETT.
